UNITED STATES PATENT OFFICE.

ROBERT S. BOLGER, OF NEW YORK, N. Y., ASSIGNOR TO INTERNATIONAL MOTOR COMPANY, OF NEW YORK, N. Y., A CORPORATION OF DELAWARE.

EXTENSION LADDER.

Application filed September 26, 1921. Serial No. 503,356.

To all whom it may concern:

Be it known that I, ROBERT S. BOLGER, a citizen of the United States, residing in the borough of Manhattan, of the city of New York, in the State of New York, have invented certain new and useful Improvements in Extension Ladders, of which the following is a specification, reference being had to the accompanying drawing, forming a part hereof.

Extension ladders as now generally constructed comprise a bed ladder, a fly ladder movable thereon and a ladder lock which holds the fly ladder in adjusted position on the bed ladder at any elevation. This lock, no matter what its form, occupies certain space on the fly ladder which would ordinarily be devoted to a round. The omission of this round at this point has proven very inconvenient and, indeed, dangerous, since it requires an abrupt change without warning of the feet of the climber from rounds in one plane to rounds in a remote plane. It has been found in practise that the omission of this round at this particular point offers a mental and physical hazard which, particularly in time of stress, is a decided disadvantage in the full usefulness of ladders of this type. This will be appreciated when it is realized that the movement of the foot from the rounds of the bed ladder to the rounds of the fly ladder which are offset several inches, or vice versa, requires care and thought unless the change comes at a natural and expected time. Where the round is provided, as in accordance with the present invention, adjacent to the end of the fly ladder and in proper spaced relationship to the next round, and in spite of the ladder lock, an additional factor of safety and convenience is introduced which is of substantial importance in this art.

In the preferred embodiment of the invention advantage is taken of the fact that ladder locks are now usually housed; this housing is formed with a hub in which may be supported a suitable round of usual construction. These locks, being placed opposite on another, will thus afford a convenient and secure support for such an additional round.

The invention will be described in greater detail hereinafter in connection with one illustrative embodiment thereof, although it will be understood as the description pro-

ceeds that other ways of securing the same advantageous results may be employed without departing from the spirit of the invention. In the drawing—

Figure 1 is a view in perspective of an extension ladder of conventional construction showing the relation of the bed ladder, fly ladder and ladder lock with the additional round supported by the casing thereof.

Figure 2 is a fragmentary view in transverse section through the bed ladder and fly ladder showing in detail the relation of the ladder lock to the rounds of the bed ladder and the relation of the additional round provided in accordance with the invention to the rounds of the bed ladder.

Figure 3 is a fragmentary detail view in front elevation of the parts shown in Figure 2, sections being broken away in the interest of clearness.

A conventional form of extension ladder, illustrated herein to insure an understanding of the object of the present invention, appears in Figure 1. The bed ladder *a* with its spaced rounds *a'* has arranged for sliding movement thereon a fly ladder *b* having spaced rounds *b'*, the raising and lowering of the fly ladder being accomplished by any suitable mechanism, indicated conventionally as a rope *c* secured at one end to the fly ladder and passing over a block *c'* secured to the bed ladder. The invention is not concerned with the form of the ladder lock employed for maintaining the fly ladder in any desired relationship to the bed ladder, but in the preferred embodiment advantage has been taken of the fact that it is now the best practise to employ only enclosed ladder locks. Of course, heretofore, the very use of ladder locks has precluded the provision of a round on the fly ladder at the points where the ladder locks are mounted, since it has not been apparent as to how a round might be mounted in the space allotted to such ladder locks. It is the principal object of the present invention to meet this deficiency by providing at its proper place in spaced relation to the next round, a round on the fly ladder in proximity to the ladder lock and that, too, without sacrificing any of the advantages or purposes. In the drawing a suitable type of lock is illustrated, the parts thereof including a hook *d*, spring *e*, and release latch *f*, all disposed in proper relation within the lock housing *g* secured to

the fly ladder b by means of bolts g' , all in a manner with which the present invention is not concerned. One such housing g with its locking mechanism is disposed at each side 5 of the fly ladder b , usually adjacent to the lower end thereof and usually spaced at about the distance of a round from the next round on the fly ladder. With the space thus occupied by the ladder lock, the climber in 10 going up or down the extension ladder has found it necessary to change his feet from the rounds a' to the rounds b' , or vice versa, practically without indication, and since these rounds lie in planes which are several 15 inches apart this change has been found to be both inconvenient and dangerous. To meet this deficiency the present invention provides an additional round B' which is on the same level as one of the upper rounds 20 a' of the bed ladder and is in proper spaced relation to the next round b' of the fly ladder b and, generally speaking, in the space where the ladder lock is found. The round B' is illustrated as a hollow steel tube supported 25 in split pinch hubs g^2 integral with the housing g of the ladder lock. To hold this round B' against displacement a bolt h is passed through the split hub g^2 and engaged by a retaining nut h' . Further, this bolt h may 30 rest within a tangential groove B^2 formed in the periphery of the round B' . The mounting at either end of the round may

be the same with respect to each housing g . From a manufacturing and mechanical standpoint there are many advantages in 35 forming the supporting hub g^2 for the round B' integral with the housing g , but it is obvious that the invention is not to be limited in this one respect since supporting devices for the round independent of the housing 40 might be employed.

In use, it will be evident that the climber when reaching the expected place for the round B' will regulate his progress accordingly and transfer his feet at the proper 45 time from the rounds a' of the bed ladder to the round B' , or vice versa, the fly ladder being complete in so far as concerns its tier of rounds.

What I claim is:

In an extension ladder, a bed ladder, a fly ladder, the lowermost round of which is provided with a tangential groove at one end, ladder locks carried at the lower end of the fly ladder, said locks serving to support the 55 lowermost round of the fly ladder on a level with one of the upper rounds of the bed ladder, one of said locks being provided with a split hub and a nut and bolt for tightening up said hub, the bolt being adapted to engage in said tangential groove.

This specification signed this 23rd day of September, A. D. 1921.

ROBERT S. BOLGER.
